Attorney,

UNITED STATES PATENT OFFICE.

CARL BAUM, OF HALLE-ON-THE-SAALE, GERMANY.

DRIVING MECHANISM FOR ROPE AND CHAIN RAILWAYS.

1,426,451.

Specification of Letters Patent. Patented Aug. 22, 1922.

Application filed March 31, 1921. Serial No. 457,550.

To all whom it may concern:

Be it known that I, CARL BAUM, a citizen of the German Republic, and a resident of Halle-on-the-Saale, Germany, have invented 5 certain new and useful Improvements in Driving Mechanisms for Rope and Chain Railways, of which the following is a specification.

Driving mechanisms, which are provided 10 with a plurality of grooved pulleys for the driving means, suffer, as it is known, from the drawback, that the first driving pulley, upon which the highest rope tension acts, is subjected to more wear and tear than the 15 subsequent pulleys. On account of their reduced diameters less rope is supplied to said last named pulleys as it would be in accordance with their circumferential velocity. The consequences thereof are heavy strain- 20 ing and sliding of the rope, unsettled and jerking operation of the driving mechanism, excessively great wearing of the rope and a high consumption of energy. A further very material drawback is that the driving 25 mechanisms, which at present in most cases are driven by electric motors of high speed require several intermediate gearings in order to obtain the slowest circumferential velocity of the driving pulleys.

It has been proposed to obviate said drawbacks by employing planet-gears with cone-shaped gear-wheels, as they are employed for instance in the construction of automobiles as equalizing gears. The disadvantage 35 of this arrangement however is that said planet-gears effect only the equalization of the tension, and not a transmission into slow speed. In order to attain the latter, numerous constructive parts must still be 40 added besides the planet-gears so that the driving mechanisms become very complicated and expensive. Driving mechanisms, actually constructed as described before, are for instance provided with 12 gear-wheels, 45 4 shafts, several hollow shafts with the appropriate bearings et cetera. A further drawback of these constructions is, that the cone-shaped planet gears produce axial thrusts, which must be obviated again by the 50 introduction of further constructive parts.

The essence of my new invention consists in the fact, that the driving motion is transmitted to the driving pulleys through a planet-gearing, of which the driving pulleys 55 form individual parts, the arrangement being made in such a manner, that by said

planet-gearing a transmission into slow speed is effected besides the equalization of the pulling force of the rope. An especially important embodiment, in which only spur-gear-wheels are employed, is the arrangement, that, when the driving pulleys are disposed abreast each other, the rope is wound first around the rotating arm of the planet-gearing, which arm is formed as rope-pulley 60 and besides is wound around the guide-wheel, which too is formed as rope-pulley, while the driving is effected by the second guide-wheel.

The transmission into slow-speed, obtained in the planet-gearing itself, is in the ratio of 1:2.

In the accompanying drawing, in which several embodiments of the subject-matter of my invention are illustrated.

Fig. 1 is a partial front-view and partial section of a gearing with internal toothing.

Fig. 2 is a side-view of said gearing, seen from the left side of Fig. 1.

Fig. 3 is a partial front view and partial section of a gearing with external toothing.

Figs. 4 and 5 represent in diagrammatical manner a side-view and a plan-view of a further form of construction of the subject matter of my invention.

In Figs. 1 and 2 the reference numerals 7 and 9 indicate the two driving pulleys, around which the rope 14 is wound, a rope-roller (tension-roller) 15 being employed in the known manner. The rope 14 enters first 90 upon the upper portion of one of the drive-pulleys and encircles the same, then runs around the tension-roller 15 and from there to the lower portion of the second drive-pulley and runs out from the upper portion 95 of said pulley.

The bearings 1, 1 are mounted on the supporting frame 16 and in these bearings the shaft 2 is fixedly arranged. On said shaft 2 is loosely rotatable the driving belt-pulley 100 3, to which the gear-wheel 4 (which corresponds to a guide-wheel of the planet-gearing) is rigidly connected. The belt pulley 105 is driven in the known manner from a motor or a counter-shaft. The gear-wheel 4 meshes with the gear-wheel 5, which is keyed to the shaft 6. The latter is rotatably mounted in the driving-pulley 7 (which corresponds to the rotating arm of the planet-gearing) and supports the pinion 8, which 110 is keyed to it, said pinion meshing with the internal toothed rim of the drive-pulley 9.

(The latter corresponds to the second guide-wheel of the planet-gearing, while the parts 5 and 8 correspond to the rotating-wheels.)

When now the belt-pulley 3 is driven in 5 the direction of the arrow 10, the planet-wheel 5 will rotate in the direction of the arrow 11. The pinion 8 has the same direction of rotation and accordingly effects a rotation of the pulley 9 in the direction of 10 the arrow 12. As the pulley 7 too is loosely mounted upon the shaft 2 and as the shaft 6 is mounted in said pulley, the latter is rotated by the counter-pressure, produced by the pinion, in the direction of the arrow 15 13. The shaft 6 and with it the gear-wheel 5 accordingly rotate concentrically to the centre of the shaft 2. The pressure, caused by the teeth of the pinion 8, effects an exactly equally strong counter-pressure on the 20 bearing of the shaft 6. Accordingly the pulleys 7 and 9 must rotate, if the load of the same is assumed to be equal, with the same circumferential velocity, but in opposite directions. If it is now further assumed, that first the pulley 7 is braked or 25 locked, then the gear-wheels act as ordinary transmission wheels and the circumferential velocity of the pinion 8 is completely transmitted to the internal toothed rim of the pulley. If however it is assumed, that the pulley 9 is braked or locked, the pinion 8 will move along the internal toothed rim of said pulley and thereby carries along the pulley 7 with the aid of the shaft 6. The 30 tooth pressure (action) on the pulley 9 and the counter-pressure (reaction) on the pulley 7 have always exactly equal strength, and here always a theoretically perfect state of equilibrium must prevail. The latter can 35 not be disturbed in any way by unequal wear of the driving pulleys or by thickening of the rope or other operative conditions, as a change of the load of one of the pulleys results immediately in an equivalent 40 change of the load of the other pulley. The circumferential velocity of the pinion is partly transmitted actively on the pulley 9 and to the other part reactively on the pulley 7. Accordingly a transmission into 45 slow speed in the ratio of 1 to 2 takes place without regard to the ratio of transmission of the gear-wheels. This mode of operation represents the essence of the present invention. All other advantages, as conceivably 50 slightest expenditure of material, the presence of only few constructive parts, lowest cost of manufacture and slight need of space are the results of this novel transmission into slow speed.

55 The form of construction illustrated in Fig. 3 corresponds exactly to that shown in Figs. 1 and 2 with the exception of the driving pulley 9, which is provided with an external toothed rim, instead of an internal one.

In the form of construction illustrated in Figs. 4 and 5 the driving belt-pulley 17 is loosely rotatably mounted on the shaft 18 and is rigidly connected to the gear-wheel 19. The latter meshes with the gear-wheel 70 20. Within the gear wheel 21 a shaft is loosely rotatably mounted, to which the gear-wheel 20 and the pinion 23, meshing with the internal toothed rim of the driving pulley 22, are keyed. The rotating 75 movement is transmitted to the driving pulley 26 by means of the gear-wheels 24 and 25. The pulley 27 represents the usual tensioning pulley or roller. The directions of rotation of the wheels and pulleys are 80 indicated in Fig. 4 by arrows. The pulley 22 and the gear-wheel 21 are shown in this view as arranged behind each other and have different directions of rotation. The arrow indicated by *a* shows the direction 85 of rotation of the pulley 22, while the not indicated arrow shows the direction of rotation of the gear-wheel 21. The course of the rope is also indicated by arrows. As it may be seen from the drawing, in this 90 form of construction the rope pulleys 22 and 26 are not arranged abreast each other, but are mounted in the same plane behind each other on different shafts.

Having thus particularly described the 95 nature of my invention, what I claim as new and desire to secure by Letters Patent of the United States is:

1. Driving mechanism for rope- and chain-railways comprising in combination 100 two driving pulleys, a tensioning roller for double rope-winding and a planet gearing, of which said driving pulleys form parts, the driving force being applied through said planet gearing in such a manner as to equalize simultaneously the pulling force of the rope and to effect a transmission into slow speed.

2. Driving mechanism for rope- and chain-railways comprising in combination 110 two driving-pulleys, arranged abreast each other, a tensioning roller for double rope winding, and a planet, gearing, of which said driving pulleys form parts, the rope being wound once around the driving pulley, corresponding to the rotating arm of the planet-gearing and further around the driving pulley corresponding to one of the guide-wheels of the planet gearing and the driving power being applied at the second 115 guiding wheel so as to effect besides the equalization of the pulling force of the rope through the planet gearing a transmission into slow speed in the ratio of 1:2.

In testimony whereof I affix my signature in presence of two witnesses.

CARL BAUM.
